- International Search Report in corresponding PCT Application No. PCT/US2012/027602, dated Aug. 20, 2012, in 16 pages.
- International Preliminary Report on Patentability in corresponding PCT Application No. PCT/US2012/027602, dated Sep. 19, 2013, in 11 pages.
- Office Action in corresponding Canadian Patent Application No. 2828006, dated Feb. 20, 2018, in 3 pages.
- Office Action in corresponding Canadian Patent Application No. 2828006, dated Oct. 25, 2018, in 3 pages.
- Office Action in corresponding Chinese Patent Application No. 201280020813.6, dated Jun. 25, 2015, in 9 pages.
- Office Action in corresponding Chinese Patent Application No. 201280020813.6, dated Feb. 19, 2016, in 10 pages.
- Office Action in corresponding European Patent Application No. 12713421.1, dated May 10, 2016, in 5 pages.
- Office Action in corresponding European Patent Application No. 12713421.1, dated Mar. 10, 2017, in 5 pages.
- Office Action in corresponding European Patent Application No. 12713421.1, dated Mar. 23, 2018, in 5 pages.
- Office Action in corresponding European Patent Application No. 12713421.1, dated Feb. 4, 2019, in 5 pages.
- Office Action in corresponding European Patent Application No. 12713421.1, dated Dec. 13, 2019, in 5 pages.
- International Search Report in corresponding PCT Application No. PCT/US2013/024906, dated Jul. 22, 2013, in 11 pages.
- International Preliminary Report on Patentability in corresponding PCT Application No. PCT/US2013/024906, dated Aug. 12, 2014, in 7 pages.
- International Search Report in corresponding PCT Application No. PCT/US2013/025227, dated Feb. 25, 2014, in 15 pages.
- International Preliminary Report on Patentability in corresponding PCT Application No. PCT/US2013/025227, dated Aug. 21, 2014, in 10 pages.
- Office Action in corresponding Canadian Application No. 2862506, dated Nov. 23, 2018, in 7 pages.
- Office Action in corresponding Chinese Application No. 201380016516.9, dated Mar. 28, 2016, in 12 pages.
- Office Action in corresponding Australian Patent Application No. 2016201439, dated May 14, 2020, in 6 pages.
- Office Action in corresponding Australian Patent Application No. 2016201439, dated Feb. 15, 2021, in 8 pages.
- Office Action in corresponding Chinese Patent Application No. 201610127661.X, dated Nov. 1, 2019, in 10 pages.
- Office Action in corresponding Chinese Patent Application No. 201610127661.X, dated Aug. 4, 2020, in 27 pages.
- Office Action in corresponding Chinese Patent Application No. 201610127661.X, dated Mar. 3, 2021, in 24 pages.
- Extended Search Report in corresponding European Patent Application No. 16158630.0, dated Aug. 3, 2016, in 10 pages.
- Observations by Third Party in corresponding European Patent Application No. 16158630.0, dated Dec. 13, 2019, in 32 pages w/machine translation.
- Examination Report in corresponding European Patent Application No. 16158630.0, dated Jan. 20, 2020, in 6 pages.
- Observations by Third Party in corresponding European Patent Application No. 16158630.0, dated Jan. 4, 2021, in 8 pages.
- Office Action in corresponding European Community Design Patent Application No. 002764860-0001, dated Sep. 7, 2015, in 4 pages.
- Office Action in corresponding Japanese Patent Application No. 2016-015496, dated Oct. 18, 2016, in 3 pages.
- Office Action in corresponding Chinese Patent Application No. 201810226508.1, dated Mar. 3, 2021, in 23 pages.
- Extended Search Report in corresponding European Patent Application No. 18161558.4, dated Oct. 24, 2018, in 11 pages.
- Office Action in corresponding European Patent Application No. 18161558.4, dated Jun. 12, 2019, in 4 pages.
- Summons to attend oral proceedings in corresponding European Patent Application No. 18161558.4, dated Mar. 2, 2020, in 6 pages.
